VALVE PIPE WITH GROOVED BOWL

Carroll Price Brooks, Philadelphia, Pa.

Application June 19, 1950, Serial No. 168,984

4 Claims.

(Cl. 131—198)

1. This invention relates to tobacco pipes and more particularly to pipes comprising a tobacco bowl, a stem preferably made integrally with the pipe and a mouth piece removably connected with the stem.

The primary object of the invention is to provide a pipe of the character indicated above enabling a smoker to obtain a cool dry smoke by permitting and regulating the admission of fresh atmospheric air into the stem during the process of smoking.

Another object of the invention is to provide a pipe of the character indicated above having a plurality of grooves formed in the inside surface of the tobacco bowl and extending downwardly thereof in order to obtain a greater smoking surface and to enlarge the cubic contents of the bowl.

A further object of the invention is to provide a pipe of the character indicated above having a plurality of grooves formed in the outside surface of the bowl in order to enlarge the surface of the bowl exposed to the cooling influence of the atmospheric air, whereby the condensation action is reduced and a drier smoke is obtained.

The invention consists in the details of construction and in the combination and arrangement of the several parts of my improved valve pipe with grooved bowl whereby certain advantages are attained, as will be hereinafter more fully set forth.

In order that my invention may be better understood, I will now proceed to describe the same with reference to the accompanying drawings, wherein:

Figure 1 is a top view in plan of a preferred embodiment of a pipe in accordance with the present invention.

Figure 2 is a side view in section of the pipe.

Figure 3 is a view in section taken on line 3—3 in Figure 2, and

Figure 4 is a view in section taken on line 4—4 in Figure 2.

The tobacco pipe as herein embodied comprises a tobacco bowl 10 of conventional shape and made of any suitable material and a stem 11 preferably made integrally with the bowl 10. In order to enlarge the cubic contents of the bowl 10 a plurality of grooves 12 are formed in the inner surface of the bowl and this arrangement increases also the smoking surface of the bowl.

To prevent or at least to reduce condensation inside the pipe a plurality of grooves 13 is provided in the outside surface of the bowl whereby the cooling surface of the bowl exposed to con-

tact with fresh atmospheric air is increased and condensation inside the pipe is reduced to a minimum and a cool dry smoke is obtained.

5 A mouth piece 14 is secured to the rear end portion of the stem 11 in any suitable conventional manner. The rear end portion 15 of the conventional bore 16 of the pipe stem 11 is enlarged and a conventional condenser 17 is provided in said enlarged bore portion.

10 The mouth piece 14 is provided with a longitudinal bore 18 and the front end portion 19 of the mouth piece 14 is reduced in diameter and fits snugly into a counter bore 20 provided on the rear end portion of the enlarged bore portion 15 of the stem 11. The condenser 17 is supported by a counterbore 21 of the front end portion of the bore 18 of the mouth piece 14.

20 A metal ring 22 or the like surrounds the rear end portion of the stem 11 and a second ring 23 of a small diameter is secured or formed on top of the ring 22. A hole 24 extends through the wall of the counterbore 21 in the mouth piece 14, a hole 25 extends through the ring 22, a hole 26 extends through the ring 23, a hole 24' extends through the stem 11 and all these holes are disposed coaxially.

30 A blind hole 27 is provided in the rear surface of the tobacco bowl 10 and is arranged coaxially with the ring 23. An adjusting rod 28 is rotatably supported by the blind hole 27 and the ring 23. Adjacent the front end of the adjusting rod 28 a hole 29 extends through said rod at an acute angle to the axis thereof and a hole 30 in the pipe communicates with the bore 16 of the stem 11 and is arranged so that the hole 29 in the adjusting rod 28 is adapted to communicate with it upon proper rotary adjustment of the rod 28.

40 A diametrical hole 31 is provided in the rod 28 adjacent the rear end thereof and is disposed so that it will be coaxial with holes 24, 24', 25 and 26 when the holes 29 and 30 communicate with each other.

The adjusting rod 28 extends only partway through the ring 23, the rear end portion of which is threaded as at 32. A screw 33 engages the thread in the ring 23, closes the rear end thereof and engages the rear end of the adjusting rod 28 preventing the same from accidental removal and axial displacement.

50 A small adjusting lever 34 is fastened onto the adjusting rod 28 to facilitate the manipulation of said rod and is preferably made from wire.

A slot 35 is provided in the rear end surface of the stem 11 and extends radially from the counterbore 20 in the stem. A notch 36 in the

rear end surface of the ring 22 communicates with the slot 35.

In use the adjusting rod 28 is rotatably positioned so that the air inlet holes 24, 24', 25 and 26 in the rear end portion of the stem 11 and the air inlet hole 30 in the front end portion of said stem are closed to prevent fresh air from entering the bore 16 of the stem 11. The pipe bowl 10 is filled with tobacco which is lit in the conventional manner. The valve holes 24, 24', 25, 26 and 30 are opened by rotating the adjusting rod 28 so that the hole 27 in said rod is aligned with the hole 30 and the hole 31 is aligned with the holes 24, 24', 25 and 26 permitting fresh air to be sucked into the bore 16 of the stem 11 to assure a cool smoke.

I claim:

1. A tobacco pipe of the class described having a bowl provided with a hole in the side thereof, a stem and a mouth piece including an annular member surrounding the rear end portion of the stem, a second annular member on the first annular member, an air inlet hole extending diametrically through the two annular members and a second air inlet hole extending radially of the stem and arranged coaxially with the first air inlet hole, and an adjusting rod rotatably supported by the second annular member of the said bowl and provided with a diametrical hole in the bowl and provided with a diametrical hole passing through the rod and adapted to be disposed coaxially with the air inlet holes by proper rotary adjustment of the adjustment rod.

2. A tobacco pipe of the class described having a bowl provided with a hole in the side thereof, a stem and a mouth piece including an annular member surrounding the rear end portion of the stem, a second annular member on the first annular member, an air inlet hole extending diametrically through the two annular members and a second air inlet hole extending radially of the stem and arranged coaxially with the first

air inlet hole, an adjusting rod rotatably supported by the second annular member and the said hole in the bowl and provided with a diametrical hole passing through the rod and adapted to be disposed coaxially with the air inlet holes by proper rotary adjustment of the adjustment rod, and means for preventing accidental removal and axial displacement of the adjustment rod.

3. A tobacco pipe as set forth in claim 2, wherein said means comprises a screw threadedly engaging the rear end portion of the second annular member and abutting the rear end of the adjusting rod thereby preventing accidental axial movement thereof.

4. A tobacco pipe as set forth in claim 2, wherein said means comprise a screw threadedly engaging the rear end portion of the second annular member and abutting the rear end of the adjusting rod thereby preventing accidental axial movement thereof, and a lever on the adjusting rod for facilitating the rotary adjustment of said rod.
